Primary Examiner — Selina Sikder(74) *Attorney, Agent, or Firm* — John A. Kramer; Global Patent Operation(57) **CLAIM**

The ornamental design for an enclosure for electronic device, as shown and described.

DESCRIPTION

FIG. 1 is a perspective top view of an enclosure for electronic device depicting a first embodiment of a new design;

FIG. 2 is a top plan view thereof;

FIG. 3 is a bottom plan view thereof;

FIG. 4 is an end view thereof;

FIG. 5 is an opposite end view thereof;

FIG. 6 is a side view thereof;

FIG. 7 is an opposite side view thereof; and,

FIG. 8 is a perspective bottom view thereof.

The broken line portion of the drawings is included to show unclaimed subject matter only and forms no part of the claimed designs.
